UNITED STATES PATENT OFFICE

168,238

HOLDER FOR COSMETICS OR SIMILAR ARTICLE

Arnold Perlman, Greenwich, Conn., assignor to Helene Pessl, Inc., New York, N. Y., a corporation of New York

Application September 3, 1952, Serial No. 21,291

Term of patent 14 years

(Cl. D86—10)

To all whom it may concern:

Be it known that I, Arnold Perlman, a citizen of the United States, residing at Greenwich, in the county of Fairfield and State of Connecticut, have invented a new, original, and ornamental Design for a Holder for Cosmetics or Similar Article, of which the following is a specification, reference being had to the accompanying drawing, forming part thereof.

In the drawing

Fig. 1 is a top plan view of the holder for cosmetics or similar article, showing my new design; Fig. 2 is a front elevation view, Fig. 3 is a bottom plan view, Fig. 4 is a rear perspective view, and Fig. 5 is a sectional view thereof taken on line

5—5 of Fig. 2 and looking in the direction of the arrows.

I claim:

The ornamental design for a holder for cosmetics or similar article, substantially as shown.

ARNOLD PERLMAN.
